UNITED STATES PATENT OFFICE.

JAMES T. HAMBAY, OF PITTSBURG, PENNSYLVANIA.

SWITCH-STAND.

SPECIFICATION forming part of Letters Patent No. 324,838, dated August 25, 1885.

Application filed February 5, 1885. (No model.)

To all whom it may concern:

Be it known that I, JAMES T. HAMBAY, a citizen of the United States, residing at Pittsburgh, in the county of Allegheny and State of Pennsylvania, have invented or discovered certain new and useful Improvements in Switch-Stands, of which improvements the following is a specification.

In the accompanying drawings, which make part of this specification, Figure 1 is a front elevation of my improved double-semaphore switch-stand. Fig. 2 is a side elevation of the same. Fig. 3 is a detail view, on an enlarged scale, of the signal-operating mechanism.

My invention relates to an improvement in signal mechanism for switches and crossings, and has for its object the setting and locking of the signals at facing-point switches in proper positions to indicate the intended adjustment of the switch-rails prior to such adjustment, and for simultaneous setting of danger and safety signals at railroad crossings; and to these ends my invention consists in the construction and combination of parts, all as more fully hereinafter described and claimed.

The switch-stand consists of a suitably-formed base-plate, 1, provided with legs or uprights 2, on which is formed or secured the circular plate 3. On this circular plate, at one side of its center, is formed the vertical lug 4, said lug being provided at its upper end with the block 5, said block projecting inwardly over the center of the plate 3, and being provided with a socket in its upper side for the reception of the post or pillar 6, extending a considerable distance above the main portion of the stand.

To the post 6 are secured at different heights the brackets 7, on which are supported the lanterns 8, and to the post or pillar are pivoted the semaphores 9 and 10, of the usual construction, the pivoted points of such semaphores being located in or adjacent to horizontal planes passing through the center of the illuminating-apertures of the lanterns. (See Fig. 1.)

To the semaphores adjacent to their pivotal points are attached rods 11 and 12, the lower ends of said rods being connected to one of the arms of each of the bell-crank levers 13

and 14, which are pivoted to a common pivot secured to a lateral projection on the block 5. (See Fig. 2.) In the opposite ends of these bell-crank levers are formed the connected slots 15 and 16, arranged at right angles to each, the slots 15 being parallel to the opposite arms of the bell-crank levers, and having a length approximately equal to half the movement of the sliding block 17. This sliding block is provided on its upper side with flanged lugs 18, constructed to fit in suitable ways, 19, formed on the under side of the overhanging block 5. On one side of the sliding block 17 is formed the upwardly-projecting lug 20, provided with a pin, 21, projecting into and adapted to engage the slots 15 and 16 in the bell-crank levers 13 and 14.

In the under side of the block 17 is formed a circular groove for the reception of the short end of the switch and signal operating lever 22, said lever being pivoted to the head-block 23, secured to the upper end of the vertical shaft 24, mounted in the lower or main portion of the stand.

On the lever 22, in the rear of its pivotal point, is formed a lug, 25, adapted in certain positions of the lever and head-block to rest upon the plate 3 near its periphery, thereby holding the lever in a horizontal position.

In the plate 3 are formed slots 26, (shown in dotted lines, Figs. 1 and 3,) said slots being located in the plane of movement of the sliding block 17, and constructed, when the lever 22 is turned into such plane on either side of the stand, to receive the lug 25 and permit of the lever 22 being turned down into a vertical position, as shown in the several views; and in line with the slots 26 are notches for the reception of the handle part of the lever 22 when turned down, thereby preventing any rotation of the head-block until the lever is turned up into a horizontal position.

The lower end of the vertical shaft 24 is provided with a crank-arm, 27, or any other suitable means for connection with the switch-rails, whereby said rails may be operated by the rotation of the vertical shaft 24.

It will be observed that the slots 16, or what may be termed the "operative slots," in the bell-crank levers 13 and 14—as the bell-cranks are moved only when the pin 21 is in said

slots—are arranged parallel to the crank-arm in which they are formed and at opposite ends of the long slots 15, arranged at right angles to said arms and the slots 16, so that only one 5 of the levers is operated at each end of the movement of the sliding block. The semaphores 9 and 10 are so connected to the bell-crank levers 13 and 14 that both may be brought to "danger" simultaneously, or one 10 may be brought to "danger" and the other to "safety," but both cannot be brought to "safety" at the same time.

In describing the operation I will start with the main line open, the upper semaphore being 15 inclined downward, indicating "safety," and the lower semaphore standing at right angles to the signal-post, indicating "danger," all as fully shown in Fig. 1. When the semaphores are in this position the pin 21, connected to 20 the sliding block 17, is located in the operating slot 15 of the bell-crank 13 of the upper or main-line semaphore, and is also at the end of the horizontal slot 16, of the lower or switch-semaphore bell-crank 14. Upon raising the 25 handle of lever 22, preparatory to setting the switch, the sliding block 17, and pin 21 connected thereto, are moved inward by the short end of the lever 22. As the pin 21 is moved inward it engages the inner wall of the slot 16 in the bell-crank 13, and turns said crank until 30 its upper arm assumes a horizontal position, and its slot 15 lies in the path of the movement of the pin 21. During the above operation of the crank 13 this pin 21 has been moving 35 along the slot 16 in the crank 14, thus holding said crank and its semaphore stationary, and as the lever 22 assumes a horizontal position the pin 21 enters the slot 16 of the crank 13 and moves out of line with the pivotal point of 40 said bell-crank, thus locking it and its semaphore, which has been turned to "danger" by the movement of the pin and crank above stated. The movement thus far imparted to the block 17 and pin 21 has been sufficient to 45 move said pin about midway of the slots 16 in both bell-cranks, and thus lock both of said cranks and both semaphores at "danger." The lever 22 is now turned around horizontally one hundred and eighty degrees, thus 50 turning the vertical shaft 24, and shifting the switch-rails so as to open the switch and close the main line. During this horizontal movement of the lever it is held in a horizontal position by the lug 25, resting upon the plate 55 3. When the lever has been turned around so as to bring it in line with the slot and notch on the opposite side of the plate, it is turned down, thus pulling the block 17 toward the left in Fig. 3. As the block moves to the 60 left, the pin moves along the slots 16 in the bell-cranks 13 and 14; but as this movement of the pin is at an angle to the crank-arm, or to the radii of the circle described by said arm in its movement, the crank-arm 13 is 65 firmly locked as soon as the pin enters the long slot. While the pin 21 is moving along the slot 15 in the bell-crank 13 away from the

radial slot 16, it is moving along the corresponding slot in the bell-crank 14 toward the radial slot therein, and just before the block 70 17 reaches the limit of its movement the pin 21, striking the outer wall of the radial slot in the bell-crank 14, will cause said crank to turn on its pivot, thereby bringing the radial slot into the line of movement of the pin, 75 which will, on the completion of the movement, enter the radial slot and lock the switch-semaphore at "safety." When the main line is to be opened, the above movements are 80 reversed, both signals being first thrown to "danger" and locked, the switch-rails shifted, and the main line signal set to "safety" and locked.

A stand provided with the semaphores and their operating mechanism, the former being 85 arranged at right angles to each other, may be located at the intersection of two main lines, one of the semaphores being arranged at right angles to one of the intersecting lines, and the other semaphore similarly disposed 90 with relation to the other line. When employed for intersecting lines, the switch-operating mechanism is omitted. In some instances I propose to connect a distant main-line signal with the crank operating the home 95 main-line signal, and also when the apparatus is employed for intersecting lines to connect distant signals with the bell-cranks of both home-signals, thus providing a more perfect guard for switches and crossings. 100

I claim herein as my invention—

1. In a signal mechanism, the combination of two semaphores or other signals, a reciprocating block or slide, and independent signal-operating mechanisms, each engaging said 105 block and adapted in a single movement of the block to shift one of said signals from "danger" to "safety" and the other from "safety" to "danger," and to lock the signals in such changed positions, substantially as set forth. 110

2. In a signal mechanism, the combination of two semaphores or other signals, one of which is normally locked at "danger" and the other at "safety," a reciprocating block or slide, and independent signal-operating mechanisms, 115 each engaging said block and adapted on a single movement of the slide to reverse the positions of the signals and lock them in such reversed positions, substantially as set forth.

3. In a switch and signal mechanism, a rotating switch stem or shaft, in combination with a lever pivoted to said shaft and adapted to lock the shaft as against rotary motion, and two semaphores or other signals, one of which is normally at "danger" and the other at "safety," adapted to be reversed and locked in reversed positions by the locking and unlocking movements of the lever, substantially as set forth. 120

4. In a switch and signal mechanism, a rotating switch stem or shaft, in combination with a lever pivoted to said shaft and adapted to lock said shaft as against rotary motion, two semaphores or other signals and suitable 130

connecting mechanism, whereby the unlocking movement of the lever will set both signals at "danger," and the locking movement will set one signal at "safety" and lock the other at "danger," substantially as set forth.

5. In a switch and signal mechanism, a rotating switch stem or shaft, in combination with a lever pivoted to said shaft and adapted to lock the shaft as against rotary motion, two 10 semaphores or other signals, and suitable connections between the lever and signals, whereby said signals are set and held at "danger" by the unlocking of the lever and during the shifting of the switch-rails, and are set and 15 locked in such positions as indicate the position of the switch-rails by the locking movement of the operating-lever, substantially as set forth.

6. In a signal mechanism, the combination

of two main-line signals and a switch signal, 20 and reciprocating block and suitable connections between the block and signals, whereby said signals may be operated by a single movement of the block, so as to indicate the condition of the main line and switch, substantially as set forth. 25

7. In a signal mechanism, the combination of two semaphores connected to two bell-crank levers, each having one of their ends slotted, as described, and a reciprocating block provided 30 with a pin adapted to engage the slots in both bell-cranks, substantially as set forth.

In testimony whereof I have hereunto set my hand.

JAMES T. HAMBAY.
